UNITED STATES PATENT OFFICE.

MITCHELL LOEB, OF NEW YORK, N. Y., ASSIGNOR TO JOINT BOARD OF SANITARY CONTROL, A NON-INCORPORATED MEMBERSHIP ASSOCIATION, OF NEW YORK, N. Y.

DESIGN FOR A BADGE.

Application filed December 22, 1924. Serial No. 11,767. Term of patent 14 years.

To all whom it may concern:

Be it known that I, MITCHELL LOEB, a citizen of the United States, residing in the city of New York, borough of Manhattan, in the county and State of New York, have invented a new, original, and ornamental Design for a Badge, of which the following is a specification, reference being had to the accompanying drawings, forming part thereof.

Figure 1 is a view in front elevation of a badge, showing my new design; Figure 2 is an edge view of the same.

I claim:

The ornamental design for a badge as shown.

MITCHELL LOEB.
